UNITED STATES PATENT OFFICE.

HERALD B. GREENING, OF HAMILTON, ONTARIO, CANADA.

WIRE LATHING.

Application filed August 12, 1922. Serial No. 581,526.

To all whom it may concern:

Be it known that HERALD B. GREENING, a subject of the King of Great Britain, residing at Hamilton, in the county of Wentworth and Province of Ontario, Canada, has invented certain new and useful Improvements in Wire Lathing, of which the following is a specification.

This invention relates to building construction and has special reference to wire lathing and building sheet.

One important object of the invention is to provide an improved general construction of devices of this character which may be readily attached to the studding of a building.

A second important object of the invention is to provide an improved form of lathing for such a device.

20 A third important object of the invention is to provide an improved arrangement for holding the lathing in supporting position on the building sheet.

With the above and other objects in view, 25 the invention consists in general of certain novel details of construction and combinations of parts hereinafter fully described, illustrated in the accompanying drawings, and specifically claimed.

30 In the accompanying drawings, like characters of reference indicate like parts in the several views, and;

Figure 1 is a face view of the device as applied to the studding of a building.

35 Figure 2 is a detail sectional view taken vertically through one of the openings in the building sheet.

Figure 3 is an enlarged detail view of a portion of the wire lathing.

40 Figure 4 is a horizontal section on the line of one of the supporting stays and showing the manner in which the flat portion of the twist lies against such stay.

45 In the embodiment of the invention herein shown the studs are indicated at S. The invention itself comprises a sheet of building paper or board 10 having vertically spaced rows of horizontally spaced openings 11 formed therein. This sheet is faced with wire lathing and, in the formation of this wire lathing there is provided a series of vertically extending strands 12 spaced to close the centers of the openings 11, the end strands forming selvedge edges and being doubled for this purpose as shown at 13. These strands are connected each to the next

adjacent strand by zigzag lacing strands 14. Each of these lacing strands has its lateral angular portions twisted around the respective vertical strand at points opposite the openings 11, as shown at 15. Also the lacing strands are twisted around the vertical strand next the first mentioned twisted portions as at 16. In the formation of these twists the doubled lacing strand is twisted 60 on one vertical strand in one direction and on the adjacent vertical strand in the opposite direction and the center portions of each twist are so arranged that the vertical and lacing strand wires lie in a plane with 65 each other. On the side opposite the wire lathing extend binding wires 17 which are horizontally disposed and lie centrally of the horizontal rows of perforations, passing at these perforations in front of the twists 70 at these points. It is to be noted that by reason of the horizontally aligned disposition of the wires at the center of the twists these twists will flatly contact with the wires 17, so that the bearing on such wires is a flat 75 bearing. It will also be noted that the double selvedge strands 13 are twisted first in one direction and then in the other so that flat contact with the wires 17 is also maintained by these strands. 80

85 There has thus been provided a simple and efficient device of the kind described and for the purpose specified.

Having thus described the invention, what is claimed as new, is:

1. The combination with a sheet of building material having vertically spaced rows of horizontally spaced openings; of a wire lathing comprising a series of vertical strands spaced to extend across the centers 90 of the openings and lacing strands each twisted about a vertical strand at the openings intersected thereby and twisted about an adjacent vertical strand intermediate the openings intersected by the 95 formerly mentioned vertical strand, and retaining wires on the opposite side of the sheet from said wire lathing and extending in front of the twisted portions at the openings. 100

105 2. The combination with a sheet of building material having vertically spaced rows of horizontally spaced openings, of retaining wires on one side of the sheet, a wire lathing on the opposite side of the sheet 110 from said retaining wires comprising a series of vertical strands spaced to extend

across the openings and lacing strands each twisted about a vertical strand at the openings intersected thereby and twisted about an adjacent vertical strand intermediate the openings intersected by the formerly mentioned vertical strand, the twists of the vertical and lacing strands at the openings being formed by doubled portions of the lacing strand twisted around the vertical strand in one direction, the twists intermediate the openings being formed by doubled portions of the lacing strand twisted around the ver-

tical strand in the opposite direction, each of said twists having the strands at each centre portion horizontally disposed whereby to lie flat against the retaining wires, said retaining wires extending in front of the twisted portions at the opening. ¹⁵

In witness whereof I have affixed my signature.

HERALD B. GREENING.
